TULLIE KING, OF REYNOLDSBURG, OHIO.

WIRE SPLICING TOOL.

1,313,488.

Specification of Letters Patent.

Patented Aug. 19, 1919.

Application filed May 15, 1919. Serial No. 297,304.

To all whom it may concern:

Be it known that I, TULLIE KING, a citizen of the United States, residing at Reynoldsburg, in the county of Franklin and State of Ohio, have invented certain new and useful Improvements in Wire-Splicing Tools, of which the following is a specification.

This invention relates to wire working implements, and more especially to tools for twisting or splicing wire by means of a revoluble head; and the object of the same is to improve the construction of such a tool.

The invention consists of improved means for retaining the wire in the slotted head, for actuating said retainer automatically but permitting it to release the wire at a certain position of the head, and in means for turning the head intermittently and for coiling or twisting one wire around the other in helical form.

Details are set forth in the following specification and claims and attention is invited to the drawings wherein:

Figure 1 is a front elevation of this tool, 25 and

Fig. 2 is a side elevation.

Fig. 3 is a section through the sleeve and head, showing the latter turned so that its slot is out of register with the mouth of the 30 sleeve.

Fig. 4 is a section on the line 4—4 of Fig. 3.

Fig. 5 is a perspective view of the tool at work.

35 A handle 1 which is straight in the present case carries at one end a sleeve 2 constituting a bearing for the head to be described below, the sleeve being split at one side at 3 to produce a mouth which is herein shown as 40 opening through the wall of the sleeve at its outer side directly opposite the handle. At a point about quartering to this mouth the sleeve has its wall pressed outward so as to produce an internal chamber 4 for a purpose 45 yet to appear. Formed on the handle are perforated lugs constituting guides 5 through which slides the stem 6 of a pawl 7, and a spring 8 surrounds the stem between the head of the pawl and the rear guide so 50 as to project the pawl normally to its work.

Rotatably mounted within the bearing or sleeve 2 is a head 12 whose general contour is cylindrical so that it fits the sleeve as best seen in Fig. 3, and this head is slotted radially throughout its entire length from its axis to its periphery, as seen at 14. A plate

10 is attached by screws 11 or otherwise to one end of the head and bears against one end of the sleeve 2, while the other end of the head is notched and toothed on its periphery to constitute a ratchet 17 adapted to be engaged by the said pawl 7. Thus the plate and the ratchet retain the head in the sleeve, and the swinging of the handle and resultant movement of the pawl will cause 65 the step by step rotation of the head in the sleeve.

The wire retainer best seen in Fig. 4 comprises a pair of pins 20 mounted in holes 21 extending from the slot 14 outward at right angles thereto, and the pins have heads at their outer ends which may well be made in the form of a single member or short bar 22 connecting the two pins and adapted to stand within a peripheral recess 26 in the 75 head 12, the recess being shaped to receive the bar or head element for the pins when it is pressed inward as seen in Fig. 3. This element, however, is of a size to move outward into the chamber 4 when the head 12 80 turns to the proper point, which it will do at a time when the slot 14 registers with the mouth 3. For moving said bar outward, a spring 24 is mounted in a socket 25 as seen in Fig. 4.

85 Finally a spreader in the shape of a curved cam 30 is formed on one end of the rotary head, and preferably on that end which carries the ratchet 17, the cam curving around the inner end of the slot 14 as shown in Figs. 90 1 and 5 and increasing in thickness from its low end 31 to its high end 32, while a hole or eye 33 is formed through its body radially of the head at a point adjacent said high end. This spreader may well be cast integral with the head.

With this construction of parts, the use of the tool as best seen in Fig. 5 is as follows:

The wires W and W' are to be spliced, and their inner ends are lapped as shown 100 and held by pliers P, the inner end of the wire W' being upturned as at U and passed through the eye 33. The other wire W is moved to the bottom of the slot 14, where it is retained by the tips of the pins 20 when 105 they are projected part way into or perhaps entirely across said slot as seen in Fig. 3. The operator holds the pliers with one hand, and manipulates the handle 1 with the other, and the pawl-and-ratchet mechanism causes 110 the rotation of the head within the sleeve. The eye 33 carries the upturned end U of

one wire around the body of the other, and at each revolution the spreader cam 30 causes the entire head to move along the wire W just the thickness of the wire being 5 coiled around it, so that a neat helical coil is produced. After this end of the wire has been consumed, the slot is set in alignment with the mouth, when the spring 24 causes the retainer automatically to release the wire 10 at the bottom of the slot, and the tool can be drawn off the same and reversed and the operation is repeated in the opposite direction on the end of the other wire.

Having thus described the invention, what 15 is claimed as new is:

1. The herein described tool having a head provided with a radial slot for receiving a wire, a pin movable in the head to project its inner end across the slot near the bottom 20 thereof, a bar at the outer end of the pin, the head having a recess for said bar, yielding means normally unseating the bar from the recess and retracting said pin, and means for seating the bar in said recess at will.
2. The herein described tool having a head provided with a radial slot for receiving a wire, parallel pins movable in the head on lines at right angles to the plane of said slot to project their inner ends across the 30 slot near the bottom thereof, a bar connecting the outer ends of the pins, the head having a recess for said bar, yielding means normally ejecting the bar from the recess for retracting said pins, and manually operable 35 means for pressing the bar into said recess at will.
3. In a wire working tool, the combination with a handle, and a sleeve carried thereby and split at one point and internally 40 chambered at another, of a head rotatably mounted in the sleeve and having a radial

slot and a radial hole intersecting said slot, wire retaining means movably mounted in said hole and borne into active position by the walls of the sleeve but permitted to move 45 outward into said chamber when the split and slot aline, a spring for so moving said means outward, and means for turning said head.

4. In a wire splicing tool, the combination 50 with a handle, and a sleeve carried thereby and split at one point and internally chambered at another, of a head rotatably mounted in the sleeve and having a radial slot and a radial hole intersecting said slot, 55 wire retaining devices movably mounted in said hole and borne into active position by the walls of the sleeve but permitted to move outward into said chamber when the split and slot aline, yielding means for so moving 60 said devices outward, means for rotating the head around said wire, and an eye on the head for carrying a second wire around the first, as described.

5. In a wire splicing tool, the combination 65 with a handle, a split sleeve carried thereby and having a chamber, a head rotatably mounted in the sleeve and having a slot for one wire and a hole intersecting the slot, a wire retainer movable in said hole and 70 projecting into said slot, and means for causing the automatic retraction of the retainer into said chamber when the slot alines with the split; of pawl-and-ratchet mechanism on the handle and head for rotating 75 the latter by swinging the former, and a feed cam on one end of the head around the inner end of its slot and having an eye for the other wire.

In testimony whereof I affix my signature. 80

TULLIE KING. [L. s.]
